(57) **CLAIM**

The ornamental design for a light bulb extractor, as shown and described.

DESCRIPTION

FIG. 1 is a perspective view of a light bulb extractor showing my new invention;

FIG. 2 is a top, perspective view thereof;

FIG. 3 is top, plan view thereof;

FIG. 4 is a front view thereof, the rear view being mirror symmetrical; and,

FIG. 5 is a right-side thereof, the left-side being mirror symmetrical.

The broken line structure in FIG. 1 is provided for purposes of environment and forms no part of the claimed design.
